The ornamental design for an air vehicle having rotatable and retractable pairs of wings, as shown and described.

DESCRIPTION

FIG. 1 is a perspective view showing the top, left side and front of an air vehicle having rotatable and retractable pairs of wings which forms my new design, wherein a first of the pairs of wings are shown rotated to a first position relative to one another and a second of the pairs of wings are shown in an extended position;

FIG. 2 is a top plan view thereof;

FIG. 3 is a left side elevational view thereof;

FIG. 4 is a right side elevational view thereof;

FIG. 5 is a bottom plan view thereof;

FIG. 6 is a front elevational view thereof;

FIG. 7 is a rear elevational view thereof;

FIG. 8 is a perspective view showing the top, left side and front thereof with the first pair of wings shown rotated to a second position relative to one another and the second pair of wings retracted; and,

FIG. 9 is a left side elevational view thereof.
